UNITED STATES PATENT OFFICE.

PETER T. REYNOLDS, OF BUTTE, MONTANA.

MINE-VENTILATOR.

SPECIFICATION forming part of Letters Patent No. 703,881, dated July 1, 1902.

Application filed April 17, 1901. Serial No. 56,285. (No model.)

To all whom it may concern:

Be it known that I, PETER T. REYNOLDS, a citizen of the United States, residing at Butte, in the county of Silverbow and State of Montana, have invented a new and useful Mine-Ventilator, of which the following is a specification.

My invention relates to apparatus for cooling fluids, and especially for cooling the air supplied to the lower levels of mine workings to render the atmosphere in said workings of a sufficiently low temperature to enable those there employed to work without discomfort.

To this end my invention consists of the novel arrangement of air-supply pipe, expanding-chamber, cooling-passages, freezing-mixture tank, and current-deflectors hereinafter set forth, particularly described, and claimed.

My invention is illustrated in the accompanying drawings, in which—

Figure 1 is a sectional plan view of my device; Fig. 2, an elevational view in section of same, taken on line $\alpha\alpha$ of Fig. 1; and Fig. 3, an end view showing end wall D broken away.

Referring to the drawings, A is an air-supply pipe; B, an expanding-chamber; C, a cooling-mixture tank; D, an end wall; E E, tubes rotatably mounted in walls F and G; H H, projecting outlet-spouts of tubes E E, and I a door giving access to tank C.

The particular construction and operation of my device are as follows: Air is supplied through a pipe A and is traveling in said pipe under more or less compression and high speed. The pipe A opens into the expanding-chamber B, where the air expands to a certain extent, producing a cooling effect upon itself. The wall F of the expanding-chamber B also forms the end wall of the cooling-mixture tank C. The wall F is provided with a plurality of holes arranged in vertical series, which correspond with registering holes in the other end wall G of the cooling-mixture tank. Revolvably mounted in these registering holes are tubes E E, which pass through the cooling-mixture tank C and extend or project beyond the wall G. These projecting portions of the tubes E E are bent at an angle from their axes and form spouts H H. That portion of each of the tubes E E which is within the cooling-mixture tank C is bent in

a series of sinuous bends in the same plane, which increase the cooling-surface of the tube and form the inner surface in such a manner that the air passing through is constantly agitated and thrown against the walls of the tube. The sinuous bends being in the same plane allow the tubes to offer the least obstructing surface when the tubes are rotated until the bends assume a vertical position to the icing of the cooling-mixture tank, from the door I in the top of the tank. The tubes also being arranged in vertical series, the spaces between the series will be unobstructed clear to the bottom of the tank. The projecting spouts being bent at an angle from the axes of the tubes allow the issuing air to be projected in a wide range of direction by simply turning the tubes until said spouts point in the desired direction. The spouts I themselves serve as handles by which the tubes may be turned or revolved, the bend at the spouts I serving as a crank portion. A further advantage of this construction is that the cooling mixture, ice, &c., in the tank C when it becomes caked may be shaken down to make room for more by simply revolving the several tubes by their spouts I. The feature of projecting the issuing air-current in different directions without moving the tank is very desirable when the device is put in use in the deep workings of mines and the like. The simplicity of this construction and the variety of useful functions performed by it will appeal to all.

It is obvious that I may vary the details of construction to suit varying conditions without departing from the spirit of my invention.

Having described the several parts of my device and its operation, what I claim is—

1. In a fluid-cooling device, the combination with a fluid-supply pipe and a cooling-mixture tank, of a rotatable tube passing through the interior of and passing through and journaled in the walls of said cooling-mixture tank, said tube within the interior of said tank provided with a series of sinuous bends in the same plane, one end of said tube communicating with said supply-pipe and the other end of said tube communicating with the atmosphere, substantially as described.

2. In a fluid-cooling device, the combina-

tion with a fluid-supply pipe and a cooling-mixture tank of a plurality of rotatable tubes arranged in vertical series passing through the interior of and passing through and journaled in the walls of said cooling-mixture tank, each of said tubes within the interior of said tank provided with a series of sinuous bends in the same plane, one end of each of said tubes communicating with said supply-pipe and the other ends of said tubes

communicating with the atmosphere, substantially as described.

In testimony whereof I have signed my name to the specification in the presence of two subscribing witnesses.

PETER T. REYNOLDS.
